UNITED STATES PATENT OFFICE.

ANDREW B. WILLIAMS, OF ALBERTVILLE, ALABAMA.

SCRUBBING-BRUSH.

1,160,482.

Specification of Letters Patent. Patented Nov. 16, 1915.

Application filed October 10, 1914. Serial No. 866,082.

To all whom it may concern:

Be it known that I, ANDREW B. WILLIAMS, a citizen of the United States, residing at Albertville, in the county of Marshall 5 and State of Alabama, have invented certain new and useful Improvements in Scrubbing-Brushes, of which the following is a specification, reference being had to the accompanying drawings.

10 This invention relates to new and useful improvements in scrubbing brushes and more particularly to what is known as a fountain scrubbing brush, the main object of the present invention being the provision of 15 a scrubbing brush of the above character whereby a water supply tank is supported above the brush and is adapted to provide for a continual supply of water to the brush, thus saving considerable time in applying 20 water to a floor or other surface which is being cleaned.

Another object of the present invention is the provision of a device of the above character which will possess advantages in points 25 of efficiency and durability, is inexpensive to manufacture and, at the same time, is simple in construction and operation.

With the above and other objects in view, the invention consists in the novel features 30 of construction, combination and arrangement of parts as will be hereinafter referred to and more particularly pointed out in the specification and claims.

In the accompanying drawing forming a 35 part of this application, Figure 1 is a transverse sectional view taken through my improved scrubbing brush. Fig. 2 is a front elevation. Fig. 3 is a longitudinal sectional view taken on the line 2—2, Fig. 1; and Fig. 40 4 is a detail perspective view of the brush clamp; and Fig. 5 is a detail vertical sectional view illustrating the mounting of the valve plate and operating rod.

Referring more particularly to the drawing, 45 1 indicates in general the brush member which includes the bristles 2 arranged vertically and adapted to be clamped in position at their central portions by means of the spaced parallel bars 3 and 4, the bar 3 being provided at one end with an angularly disposed perforated ear 5, while the other end thereof is provided with a suitable opening, as shown at 6, the purpose of 50 which will be hereinafter more fully set forth. The bar 4 which is arranged in par-

allel relation with the bar 3, is provided at one end with a hook 7 which curves laterally toward the body of the bar so that the outer end of the same may be inserted through the perforated ear 5 and engaged with the outer 60 edge of the opening formed in the ear, whereby to securely hold said bar against any longitudinal movement. The other end of the bar 4 is provided with an angular extension 8 adapted to be inserted through the 65 opening 6 in the bar 3 and is provided at its outer end with screw threads whereby a wing nut 9 may be readily engaged therewith after the same has been inserted through the opening 6 to securely retain the 70 bars in their effective positions.

It will be noted in Fig. 3 that the bristles 2 are arranged between the bars 3 and 4 and are clamped in position by having the nut 9 threaded upon the angular end 8, after it has 75 been inserted through the opening 6. Supported above the brush member 1, is a tank 10 securely held in an upright position by means of the supporting strap 11, the upper 80 ends of which are arranged in parallel relation and removably connected by means of the bolts 11'. The intermediate portions of the straps 11 embrace the tank 10, while the lower ends thereof are arranged upon opposite sides of the bar 3 and riveted or otherwise secured thereto. From this it will be 85 apparent that the supply tank 10 will be supported directly above the brush 1, whereby a continual supply of water will be conveyed to the brush.

Secured to the lower side of the tank 10 is a supply trough 12, one end of which projects beyond one end of the tank 10 and is provided with an upwardly extending wall 13 forming an open chamber so that the valve plate *a* may be readily actuated within its guides to open and close the opening 14 formed in the end of the tank, so that the trough 12 may be supplied with a sufficient amount of water for the brush. The 100 valve plate *a* is actuated by means of a rod *b*, the upper end of which projects through a guide member *c* and is provided with a handle *d*, whereby said rod may be reciprocated within the guide to open and 105 close communication between the tank and the trough 12. It will be noted that the bottom of the trough 12 is provided with a plurality of perforations 15, so that as the water passes through the opening 14 and 110

fills the trough 12, the water will then pass through the perforations 15 into the brush 1.

In order to prevent the volume of water within the tank from splashing from side to side and thus rendering the device difficult to operate, I provide a partition wall 14' having formed therein a plurality of openings 15' so that the water upon each side of the partition can readily pass from one side to the other. The body of the tank 10 is provided upon its upper side thereof with a suitable opening 16, which is normally closed by means of a removable cap 16', whereby the tank may be quickly and readily filled, when desired.

The handle 18, which is secured to my improved fountain brush, is provided with a forked inner end, each section of the fork being adapted to fit within suitable openings 17 formed in the bar 3 and securely retained therein in any suitable manner, whereby the brush may be readily manipulated by means of the handle 18.

From the above description, taken in connection with the accompanying drawing, it will be readily apparent that I have provided a simple and durable scrubbing brush, wherein the brush member is located directly beneath the supply tank, so that the water from the tank will pass through the brush and be readily supplied to the surface which is to be cleansed.

The supply tank 10 may be quickly and readily filled through the opening formed in the upper side thereof and which is normally closed by means of the cap member 16'.

It will be noted that by having the brush member 1 arranged directly beneath the discharge portion of the trough 12, the water will pass through the brush member, instead of dropping to one side thereof, so that it can be more evenly spread upon the surface to be cleansed.

My improved scrubbing brush, as herein shown and described, is thought to be extremely simple in construction and can be

manufactured and placed upon the market at a comparatively low cost.

While I have shown and described the preferred form of my invention, it will be obvious that various changes in the details of construction and in the proportions may be resorted to for successfully carrying my invention into practice, without sacrificing any of the novel features or departing from the scope of the invention, as defined by the appended claims.

Having thus described this invention, what I claim is:

1. A fountain brush including a supply tank, a brush member supported by the tank and arranged directly beneath the same, a discharge trough arranged beneath the tank and provided with a perforated bottom, said trough having one end thereof extended beyond one end of the tank and provided with an upwardly projecting wall, forming a chamber, one end of said tank being provided with an opening communicating with said chamber, whereby to supply the trough from the tank, a sliding valve adapted to normally close the opening in the tank, and means connected with the valve, whereby to manipulate the same and open and close communication between the supply trough and the tank.

2. A fountain brush including a supply tank, a brush member consisting of a bunch of bristles and a clamping frame for the bristles, and attaching bands connected to the frame and removably engageable about the tank for securing the brush member thereto, said bands being adapted to maintain the frame in such relation to the tank that the upper ends of the bristles are parted and engage against the tank.

In testimony whereof I hereunto affix my signature in the presence of two witnesses.

ANDREW B. WILLIAMS.
